Assistant Examiner — Woosuk K Shin

(74) Attorney, Agent, or Firm — Ballard Spahr LLP

CLAIM

The ornamental design for a container lid as shown and described.

DESCRIPTION

FIG. 1 is a perspective view of our design of a container lid in accordance with a first variant of our invention; FIG. 2 is a top view of the container lid shown in FIG. 1; FIG. 3 is a bottom view of the container lid shown in FIG. 1; FIG. 4 is a left side view of the container lid shown in FIG. 1; FIG. 5 is a right side view of the container lid shown in FIG. 1; FIG. 6 is a front view of the container lid shown in FIG. 1; and, FIG. 7 is a rear view of the container lid shown in FIG. 1. The broken lines depict portions of the container lid and environmental subject matter that form no part of the claimed design.
